P. W. BOLTON ET AL.

OUTLET VALVE

Filed Sept. 1, 1923

UNITED STATES PATENT OFFICE.

PHILIP W. BOLTON AND WILLIAM N. MINNIEAR, OF COFFEYVILLE, KANSAS.

OUTLET VALVE.

Application filed September 1, 1923. Serial No. 660,812.

To all whom it may concern.

Be it known that we, PHILIP W. BOLTON and WILLIAM N. MINNIEAR, citizens of the United States, residing at Coffeyville, in the county of Montgomery and State of Kansas, have invented certain new and useful Improvements in Outlet Valves; and we do hereby declare the following to be a full, clear, and exact description of the invention, such as will enable others skilled in the art to which it appertains to make and use the same.

This invention relates to an outlet valve particularly adapted for use in connection with tank cars.

It is aimed to provide a generally improved, simplified and more efficient valve and particularly one which uses screw threads at less locations than the valve disclosed in our pending application Serial No. 427,316, to the end that the valve may be more readily operated and manufactured and assembled at less cost.

Other objects are to provide a novel means of attachment and of the valve casting and a novel connection between the valve head or disk and its operating stem.

Various additional objects and advantages will become apparent from a consideration of the description following taken in connection with accompanying drawings.

In said drawings:

Figure 1 is a view in vertical section illustrating the improved valve as connected to a tank car;

Figure 2 is a view partly in side elevation and partly in section illustrating the valve casing;

Figure 3 is a plan view of the valve head or disk and

Figure 4 is a side elevation of said valve head or disk.

Like reference characters designate like or similar parts in the different views.

In carrying out the invention, the outlet valve is adapted for connection to a tank car for the same purpose as in our pending application 427,316 aforesaid, and the wall of such a tank car is fragmentarily suggested at A.

The valve includes a cylindrical body 10 which is partly disposed in and snugly fits an outlet opening 11 through the wall A at its lowermost portion.

Body or casing 10 has an extension 12 disposed below the wall A, which is prefer-

ably reduced in diameter and provided with screw threads at 13 in order to accommodate a securing nut 14 over-lapping the lower surface of the wall A. Integral with the casing 10 is a laterally extending securing lug 15 which overlaps the upper or inner surface of the wall A so that in combination therewith, the nut 14 will clamp the casing to the wall A. To add to the security of engagement of lug 15 with wall A and prevent possible turning of the casing, a set screw 16 is screw threaded through the lug 15 and into wall A.

Extension 12 has an inwardly extending flange 17 which supports a removable valve seat 18 whose seating surface 19 is preferably spherical as shown. Surface 19 is adapted to be normally engaged by a surface of similar shape of a valve head or disk 20 whereby the tank car and valve will be normally closed. The valve seat 18 affords a relatively narrow surface for engagement by the valve which reduces the possibility of sticking of the valve and enables the valve seat to be more rapidly and readily ground.

When the valve head or disk 20 is in open position as shown in Figure 1, the contents of the car may escape through one or more openings or ports 21 provided in the valve body in communication with the interior of the tank car, through said body, and thence through an outlet nozzle 22. Nozzle 22 is secured to the wall A by rivets or other fastenings 23 and it has recesses as at 24 in order to snugly accommodate the extension 12 and nut 14. It will be realized that the nozzle 22 like in our application 427,316 aforesaid, is attached to the car or wall A independently of the valve so that if the nozzle should be broken from the car, it will not disturb the fastening of the valve to the car.

The body or casing 10 adjacent the top has one or more vent openings or ports 25 to enable release of the air within the casing incidental to opening of the valve. At the top, the valve casing 10 has an outwardly extending flange 26 which is engaged by a cap 27 secured thereto by bolts or other fastenings 27a. A gasket 28 may be interposed between the top of the body 10 and said cap 27.

Cap 27 has a sleeve or collar 30 provided with interior screw threads as shown which are in engagement with the screw threads

31 of a rotatable valve rod 32. Valve rod 32 at its lower end has an annular flange 33 which is adapted for sliding connection with the valve head or disk 20 as the latter 5 has a key-shaped slot 34 in its upper surface. When the flange 33 is disposed in the recess or slot 34 and the disk is located within the casing 10, the latter is prevented from detachment from the stem 32. Thus 10 the valve head or disk 20 can only be applied or removed from the stem, when the latter is disengaged from the casing and which latter disengagement is only possible when the cap 27 is disengaged from body 15 10.

The valve stem 32 is adapted for actuation in any suitable manner. For instance it has a handle extension rod 35 detachably engaged therewith as it has a square socket 20 36 in which a square stud 37 of the stem 32 is disposed. A handle or operating member 38 is provided on rod 35 and the rotation or movement of the rod 35 is under control of a pawl and ratchet or lock means 25 generally designated 9 and which may be similar or substantially similar to the ratchet gear 23 and associated parts, as disclosed particularly in Figures 1 and 5 of said pending application 427,316.

30 In operation, considering that valve or disk 20 is in engagement with the seat 18 and thus closed, such valve may be opened through manipulation of the handle 38 in order to uncover the seat 18 and permit the 35 contents of the car A to discharge through the ports 21, casing 10 and nozzle 22. The handle 38 is operated in the reverse direction when it is desired to close or seat the valve 20 in order to stop the discharge of 40 the contents of the car.

Changes in the details may be resorted to provided they fall within the spirit and scope of the invention.

We claim as our invention:

A valve of the class described, in combination with a support, the valve having a casing adapted for snug disposition in an opening of the support, a lug extending integrally from the casing and overlapping the support, a fastening element securing said lug to the support, said casing having a reduced extension integral therewith and provided with exterior screw threads, a nut in engagement with said screw threads and at its upper surface intimately contacting with the shoulder of the casing at the junction of said extension therewith and intimately contacting with and overlapping the opposite face of the support to that engaged by said lug, said extension having an inwardly extending flange integral therewith, a valve seat disposed on said flange, said casing having an outlet opening through said flange, a discharge nozzle in communication with the casing provided with a recess snugly receiving said extension and said nut, said nozzle about said extension and nut intimately contacting with the under face of the support, means to secure the nozzle to the support, a valve head operable in said casing to engage and disengage said seat, said casing having vent openings and an outwardly extending flange at its upper end, a cap secured to the latter flange, said cap having a sleeve provided with interior screw threads, and an operating stem for said valve head extending through said sleeve.

In testimony whereof we affix our signatures in presence of two witnesses.

PHILIP W. BOLTON.
WILLIAM N. MINNEAR.
